US0D1074936S

(12) **United States Design Patent** (10) **Patent No.:** **US D1,074,936 S**
(45) **Date of Patent:** **** May 13, 2025**

(54) **FAUCET**

(71) Applicant: **Jiaxin Ma**, Jiangmen (CN)

(72) Inventor: **Jiaxin Ma**, Jiangmen (CN)

(**) Term: **15 Years**

(21) Appl. No.: **29/976,954**

(22) Filed: **Dec. 5, 2024**

(30) **Foreign Application Priority Data**

Nov. 27, 2024 (CN) 202430753675.8

(51) **LOC (15) Cl.** **23-01**

(52) **U.S. Cl.**

USPC **D23/242**

(57) **CLAIM**

The ornamental design for a faucet, as shown and described.

DESCRIPTION

FIG. 1 is a perspective view of a faucet, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

All the broken lines in the drawings depict portions of the faucet that form no part of the claimed design.

1 Claim, 7 Drawing Sheets
